UNITED STATES PATENT OFFICE.

JOHN FRANCIS TINER, OF SAN ANTONIO, TEXAS, ASSIGNOR OF ONE-HALF TO JOHN E. TINER, OF SAN ANTONIO, TEXAS.

ROOFING.

Application filed June 30, 1923. Serial No. 648,798.

To all whom it may concern:

Be it known that I, JOHN F. TINER, a citizen of the United States, residing at San Antonio, in the county of Bexar and State 5 of Texas, have invented a new and useful Roofing, of which the following is a specification.

This invention relates to roofing of such a nature that it may be used generally in 10 the construction of buildings, but which, however, is of especial value on roofs which are subjected to torsional strains, as in the case of freight cars.

For the last named purpose great difficulty is experienced in constructing a roof 15 which is inexpensive, and which at the same time will stand the wear and strain incident to the careening of the car. The small pitch of car roofs also increases the difficulty 20 of providing a roof which will not leak.

The objects of the present invention are to provide a roof which will be strong and durable, and may be manufactured with economy of material and labor; which is 25 sufficiently flexible to yield slightly to torsional strains and yet will be leak proof under all conditions, even though the roof is nearly level; and which may be easily applied to the sheathing in proper position 30 and secured there by a single nail.

In carrying out my invention, I have devised a roof constructed from shingles of special design, which are preferably cut from sheet metal, and so constructed that 35 they may be interlocked while being laid, in such a manner as to secure the required degree of flexibility, and yet they will be securely held in such relation to each other that the roof will be leak proof.

40 The invention will be better understood from the following detailed description taken in connection with the accompanying drawings, which illustrate the invention in its preferred form.

45 In the drawings:

Figure 1 is a plan view of a blank showing the manner of cutting the shingles therefrom without waste.

50 Figure 2 is a perspective view of a shingle.

Figure 3 is a fragmentary bottom plan view of a roof constructed in accordance with my invention.

Figure 4 is a fragmentary plan view thereof.

Figure 5 is a vertical section through the 55 roof and part of the sheathing.

The shingles from which the roof is formed are preferably stamped from sheet metal, in the form shown in Figure 2. Each shingle comprises a rectangular body portion 60 10 having a shank 11 extending downwardly from its lower edge. This shank is half the width of the body portion, and its length is equal to the lap of the shingles 65 after they are laid. The body portion 10 65 is slit, as shown at 12, near each lower corner to provide tongues 13, and a transverse slot 14 is formed near the lower end of the shank 11, which when the shingles 70 are laid is adapted to receive the adjacent 70 tongues 13 of two shingles in the subjacent course.

The manner of laying the shingles is illustrated in Figures 3, 4 and 5. The successive courses are distinguished in Figure 75 5 by the reference characters *a*, *b*, *c*, *d*, *e*, *f*, *g* and *h*. The first course *a* is made up of shingles in which the shank portion 11 is cut away, while the next course *b* is laid so as to break joints with the first course, and 80 with the lower edge of the shank 11 coinciding with the lower edge of the body portion of the first course, and with the slot 14 receiving the adjacent tongues 13 of the two subjacent shingles. The shingles of 85 the two courses *a* and *b* are bent downwardly on the line 16 about the lower edge of the roof sheathing 15 and secured by nails 17 or the like. The succeeding courses of shingles are likewise laid in a similar 90 manner with each lap equal to the length of the shank 11. Each slot 14 receives the tongues 13 of the two subjacent shingles so that the successive courses are interlocking, and each shingle is secured by one nail 18 95 or the like. This permits a certain degree of relative movement between the shingles by reason of the flexible connection between the tongues 13 and slots 14.

It is to be noted that the total length of 100 a shingle is equal to a little more than three laps, in other words, the length of the body portion 10 is a little more than twice the length of the shank portion 11. The shank

portion, although it is of less width than the body portion of the shingle, is held down in close relation with the subjacent shingles by the tongues 13, and the shingle 5 is just as effective in shedding rain as if the shank extended the entire width of the shingle.

The peculiar shape of the shingle with the reduced shank portion not only permits 10 the formation of tongues 13, which cooperate with the slots 14 to interlock the shingles, but also results in a great saving of material when the shingles are cut in the manner indicated in Figure 1. In this figure it will be noted that the line 19 separates the two rows of shingles which are cut from the blank, so that the entire width of the blank is only equal to the length of one shingle plus the length of the body portion 20 of another shingle. By cutting the shingles in this manner, the reduced shank portion results in real economy of material since the shingles may be cut without waste.

From the foregoing description it will be 25 seen that my invention embodies all the qualities desirable in a car roof so as to render the same flexible, leak proof and durable. It will be understood however that the specific structure shown and described is merely illustrative, and that modifications may be made therein, as long as such modifications embody the salient features of the invention as expressed in the appended claims.

35 What is claimed is:

1. A roof made up of interlocking shingles, each shingle having a slit near each lower corner forming a tongue, and having at its lower end a shank portion of less 40 width than the body portion, said shank portion having a transverse slot in its lower end receiving the adjacent tongues of two shingles in the subjacent course.
2. A roof made up of interlocking shingles, each shingle having a slit near each lower corner forming a tongue, and having at its lower end a shank portion of less 45 width than the body portion, said shank portion having a transverse slot in its lower 50 end receiving the adjacent tongues of two

shingles in the subjacent course, each shingle being secured in place by a single nail or its equivalent.

3. A roof made up of courses of interlocking shingles, each shingle having a rectangular portion with the side edges thereof running substantially in the same direction in which the roof slopes, said rectangular portion having a slit near each lower corner forming a tongue, a reduced shank 60 portion extending from the lower end of the rectangular portion between said slits, and having a transverse slot in its lower end receiving the adjacent tongues of two shingles in the subjacent course. 65

4. A shingle comprising a rectangular portion having two slits at one end near the corners forming tongues, and a shank portion extending from said end of the body portion between said tongues, said shank 70 portion having a transverse slot near its free end capable of receiving the adjacent tongues of two shingles laid side by side in the next course.

5. A shingle comprising a rectangular body portion having two slits extending perpendicularly from one end near the corners thereof and forming tongues, and a shank portion extending from said end of the body portion and half as wide as said body portion, whereby two rows of shingles may be cut transversely without waste from a blank as wide as the length of two shingles with the shanks overlapping, said shank portion having a transverse slot near 80 its free end capable of receiving the adjacent tongues of two shingles laid side by side in the next course. 85

6. A shingle comprising a rectangular body portion having a slit at each lower 90 corner forming tongues, the central part of the body portion being extended downwardly to form a shank of reduced width, said shank having a transverse slot long enough to receive two adjacent tongues of 95 subjacent shingles.

In testimony that I claim the foregoing as my own, I have hereto affixed my signature.

JOHN FRANCIS TINER.
